UNITED STATES PATENT OFFICE.

JOSEPH HIDY JAMES, OF PITTSBURGH, PENNSYLVANIA.

METHOD OF OXIDIZING MINERAL HYDROCARBONS.

No Drawing.

Application filed December 6, 1921. Serial No. 520,283.

In my copending applications, Serial Nos. 272,567; 281,124; 335,940 and 435,355, I have described methods and apparatus for making intermediate oxidation products from aliphatic hydrocarbons, these oxidation products ranging from alcohols through aldehyde alcohols and aldehydes to aldehyde fatty acids. The temperature in the conversion zone, as described in such applications, is below that of self-sustained combustion, preferably below a red heat, and in the range where partial oxidation products result.

As disclosed in these applications I preferably vaporize the aliphatic hydrocarbon or "bitumen" product, mix it in regulated proportions with certain proportions of air and pass the same, preferably at a temperature range of from 230° up to 450° C., depending on the conditions, the fraction used, etc., through a catalytic layer, composed preferably of oxides or compotinds of certain metals, such as molybdenum, vanadium, etc. The air is preferably fed in in regulated amounts near the theoretical combining portion or preferably in excess thereof, and the hot mixture is passed, with or without the addition of a diluting gas, such as steam, through or over a layer of the catalytic material. The catalysts employed are preferably complex oxides or compounds of metals having a varying valence, such for example, as blue oxides of molybdenum.

The condensed product contains partly oxidized bodies such as above referred to. The raw material used may be petroleum, a petroleum fraction, shale oil or a fraction thereof or the product from a low temperature distillation of coal.

Under my present invention, I subject the mineral hydrocarbon containing bodies of different molecular weights to heat treatment sufficient to convert at least a part thereof into a vapor or gaseous phase, separate from the heavier portions a lighter portion in the vapor or gaseous phase, and while the lighter portion still remains in this phase, mix it with oxygen or oxygen-containing gas and partially oxidize the same at a temperature below that of self-sustained combustion, and preferably, below a red heat, in a range which produces partial oxidation products. In one form of my process, I may distil petroleum or a fraction thereof, and thus divide it into fractions of different average molecular weights, and partially

oxidize such a separated fraction while still in the vapor or gaseous phase. In the distillation of crude or "topped" petroleum, the oil or portions thereof are vaporized in order to separate the oil into fractions of different boiling points. In my present method, I take one or more of these fractions as it is produced in the distilling, mix it with air and subject it to my partial oxidation process, as described in my above named applications, preferably that one embodied in application Serial No. 435,355, filed January 6, 1921, thereby avoiding the re-vaporization of the condensed distillate or fraction.

In carrying out the process, the distillation of the crude oil or part of said crude oil is preferably carried out by the well known methods of continuous distillation or intermittent-continuous distillation, where a series of retorts is employed with the oil or oil fractions passing through them in series; although I may employ the process in connection with intermediate distillation.

In the preferred form, with what is known as continuous distillation or intermittent-continuous distillation, a number of stills are run in series in a continuous manner, the crude oil being charged into the first still, the temperature of which is maintained at such a point as to distill over a more volatile portion of the oil. The residue from this still travels on to the next still, where a heavier fraction is distilled and so on.

In the intermittent-continuous method, the process is the same, except that the temperature is varied in the several stills, so that more than one fraction is volatilized and taken off from one or more of the stills. In combining my process with such an operation, I lead or divert part or all of the vapors coming from either of the stills or still systems, without condensing it; add the desired amount of air which may be preheated, if desired, and pass this mixture of hydrocarbon, vapor and air through a catalytic layer, or layers. In this preferred method, I admit one part of the air to the mixture passing through the first catalytic screen, additional air being admitted before passing through each of the successive catalytic screens or layers. I may also add steam or other diluent, as described therein, for temperature control, etc. This steam may be admitted to the vapor mixture before entering screen No. 1, or it may be fractionally

admitted in the same manner to that of the air. The condensing and absorbing systems may be of any desired type.

The advantages of my invention will be obvious, since I avoid revaporizing of a petroleum fraction by submitting the desired fraction or fractions while passing in vapor form from the still directly to the catalytic low-temperature oxidation process. In this way, the amount of additional heat, if any heat is imparted to the air employed, is very much reduced, and in some cases, no additional heat will be necessary. Where it is desirable, a small air preheater may be employed to preheat the air before passing into the mixture flowing to the first catalytic layer or screen. The heat treatment carried out on the mineral hydrocarbon or fraction thereof may be carried to any desirable extent or degree of temperature, so long as the separation of the lighter and heavier parts of the hydrocarbon is afforded, so that a lighter portion may be mixed with the air or oxygen containing gas for partial oxidation.

Many changes may be made in the still systems employed, the temperature of my process may be varied within certain limits, and other changes may be made, without departing from my invention.

I claim:

1. In the treatment of a liquid mineral hydrocarbon containing hydrocarbons of different molecular weights, the steps consisting of subjecting the same to heat treatment, at least sufficient to convert a part thereof into vapor or gaseous phase, separating from heavier portions thereof a lighter portion in the vapor or gaseous phase, thereafter mixing a lighter portion while still in vapor or gaseous phase with a gas containing oxygen, passing the vapor-oxygen mixture in contact with a catalyst and partially oxidizing the same within a range of temperature below that of continuous self-sustained combustion and which produces partial oxidation products.

2. In the treatment of a liquid mineral hydrocarbon containing hydrocarbons of different molecular weights, the steps consisting of subjecting the same to heat treatment, at least sufficient to convert a part thereof into vapor or gaseous phase, separating from heavier portions thereof a lighter portion in the vapor or gaseous phase, and thereafter mixing a lighter portion while still in vapor or gaseous phase with oxygen and partially oxidizing the same at a temperature below that of self-sustained combustion and in a range which produces partial oxidation products.

3. In the treatment of a liquid mineral hydrocarbon containing hydrocarbons of different molecular weights, the steps consisting of subjecting the same to a heat

treatment, at least sufficient to convert a part thereof into vapor or gaseous phase, separating from heavier portions thereof a lighter portion in the vapor or gaseous phase, and thereafter mixing a lighter portion while still in vapor or gaseous phase with oxygen and partially oxidizing the same in the presence of a catalyst at a temperature below that of self-sustained combustion and in a range which produces partial oxidation products.

4. In the treatment of a liquid mineral hydrocarbon containing hydrocarbons of different molecular weights, the steps consisting of subjecting the same to heat treatment, at least sufficient to convert a part thereof into vapor or gaseous phase, separating from heavier portions thereof a lighter portion in the vapor or gaseous phase, and thereafter mixing a lighter portion while in vapor or gaseous phase with preheated oxygen containing gas, passing the vapor-oxygen mixture in contact with a catalyst and partially oxidizing the same within a temperature range below that of continuous self-sustained combustion and which produces partial oxidation products.

5. In the treatment of mineral oil containing liquid hydrocarbons of different molecular weights, the steps consisting of distilling the same into separate fractions, mixing one of the fractions while still in the vapor phase with oxygen, and subjecting the mixture to a partial oxidation process at a temperature below a red heat.

6. In the treatment of mineral oil containing liquid hydrocarbons of different molecular weights, the steps consisting of distilling the same into separate fractions, mixing one of the fractions while still in the vapor phase with oxygen and a diluent, and subjecting the mixture to a partial oxidation process at a temperature below a red heat.

7. In the treatment of mineral oil containing liquid hydrocarbons of different molecular weights, the steps consisting of distilling the same into separate fractions, mixing one of the fractions while still in the vapor phase with preheated oxygen, and subjecting the mixture to a partial oxidation process at a temperature below a red heat.

8. In the treatment of a liquid mineral hydrocarbon containing hydrocarbons of different molecular weights, the steps consisting of subjecting the same to heat treatment at least sufficient to convert a part thereof into vapor or gaseous phase, separating from heavier portions thereof a lighter portion in the vapor or gaseous phase, thereafter mixing a lighter portion while still in vapor or gaseous phase with oxygen and partially oxidizing the same at a temperature below a red heat.

9. In the treatment of a liquid mineral hydrocarbon, containing hydrocarbons of

different molecular weights, the steps consisting of subjecting the same to heat treatment at least sufficient to convert a part thereof into vapor or gaseous phase, separating from heavier portions thereof a lighter portion in the vapor or gaseous phase, thereafter mixing a lighter portion while still in vapor or gaseous phase with oxygen and partially oxidizing the same in the presence of a catalyst and at a temperature below a red heat. 10

In testimony whereof I have hereunto set my hand.

JOSEPH HIDY JAMES.
